UNITED STATES PATENT OFFICE.

CHARLES K. PICKLES, OF PHILADELPHIA, PENNSYLVANIA, ASSIGNOR TO
JOHN A. BRILL, OF PHILADELPHIA, PENNSYLVANIA.

SWING-BACK CAR-SEAT.

No. 797,977.

Specification of Letters Patent.

Patented Aug. 22, 1905.

Application filed May 28, 1903. Serial No. 159,077.

To all whom it may concern:

Be it known that I, CHARLES K. PICKLES, a citizen of the United States, and a resident of the city and county of Philadelphia, State of Pennsylvania, have invented a new and useful Swing-Back Car-Seat, of which the following is a specification.

The object of my invention is to produce a reversible car-seat in which the back and cushion move in the same direction, the main purpose of which is to conserve space in the location and operation of car-seats. This broad invention is not mine, but forms the subject-matter of an application filed May 28, 1903, Serial No. 159,055, by William H. Heulings, Jr.; and my invention is limited to such broad invention as will be hereinafter set forth.

For a more particular description of one embodiment of my invention reference is to be had to the accompanying drawings, forming a part hereof, in which—

Figure 1 is a front elevation of a car-seat embodying one form of my invention, parts being broken away to more clearly disclose the structure. Fig. 2 is a side elevation of a car-seat embodying my improvements with parts broken away. Fig. 3 is an end elevation showing the cushion and back in their central position while the seat is being reversed. Fig. 4 is a sectional view taken on the line 4-4 of Fig. 3 looking in the direction of the arrows. Fig. 5 is an end elevation of the cushion and the cushion-support. Figs. 6, 7, 8, 9, 10, and 11 are views showing certain details of construction.

Throughout the various views similar reference characters designate similar parts.

The swing-back seat 1 is provided with any suitable support 2, at the top of which are the cross-rails 3, which are united by means of the end plates 4, to which links 5 and 6 are pivoted. The plates 4 are provided with perforations 4^a adjacent to each end, through which bolts pass to secure them to the cross-rails 3, and the plates are also provided with centrally-located perforations 4^b and 4^c, the former being below the latter. The perforations 4^b form a bearing for a shaft 14, and the perforations 4^c receive stud-pins 13, which are preferably swaged therein. The links are enlarged near their lower ends and provided with segments of annular gears 7, which are concentric with their lower pivots

8, and in the outer walls of these links, between the said pivots 8 and annular gears 7, are slots 10. The ends of the said gears 7 rest on one or the other of the cross-pieces 3, and so limit the throw of movement of the links. The links 6 are provided with spur-gears 11 at their lower ends, which are concentric with their pivots 12, which engage studs that are fixed in the upper portions of the plates 4. The parts are so proportioned and arranged that the stud 13 passes through the slot 10, and the gears 7 and 11 mesh together, so that the links always move in the same direction. The links are always moved together. The links 6 are provided with projecting lugs 15, the purpose of which will be explained below.

Each of the cross-rails 3 is provided with two brackets 16, which are secured to said rails by means of screws, and said brackets are provided with upwardly-projecting parallel and perforated ears 17. Pins 18 pass through the said perforations and secure the cushion-supports 19 by means of curved openings or slots 20 in their vertical webs 21. Bent plates 22 are fixed to the centers of the ends of the cushions 23 by screws 22^a, and the plates 22 engage the lug 15 and cause the cushion 23 to move in unison with the links. This cushion 23 may be made in any desired way and forms no part of my invention.

The free ends 24 of the links 5 are pivoted to the studs 25 on the plates 26, which are fixed to the edges of the back 27. The plates 26 are offset at 28 and provided with a slot 29, in which slides a pin 30, which is fixed at one end of the link 6. The links 5 engage the outer surface of the plates 26 and are slightly offset at 31, so as to swing clear of the lower ends of said plates, and the links 6 are secured to the inner surfaces of said plates and have a pivoted and sliding engagement with them. This construction permits the links to swing without interference with each other except that caused by the intermeshing of the gears. A holding-strap 32 may be secured to the back 27.

From this description the operation of my improved seat is obvious. Assuming the parts to be in the position indicated in Fig. 2 and the seat is to be reversed, the back is thrown into the position indicated in Fig. 3 and then on to the left of the cushion. This movement of the back causes the links 5 to

rotate the links 6, which in turn move the cushion 23 in the same direction as the back 27 and give the cushion 23 its proper inclination because of the slotted supports 19. When the seat is returned to its initial position, the same movements take place in the opposite direction, and while the back is shifted from one position to the other it is raised by the links 5 until it is clear of the cushion and remains clear until the movement terminates. The links 5 and 6 are connected by gears and the links 5 by the shaft 14, so that all parts are positively connected and act together.

While I have shown and described one embodiment of my invention, it is obvious that it may be embodied in many other forms, all of which come within the scope of my invention and are covered by the following claims.

Having thus described my invention, what I claim is—

1. In a swing-back car-seat or similar device, a sliding cushion, a back, and geared links for swinging said back and moving said cushions in unison in the same horizontal direction.

2. In a swing-back car-seat or similar device, a cushion, a back, geared links engaging said cushions and back, so that when said seat is reversed, the back and cushion are moved in the same horizontal direction.

3. In a reversible car-seat, the combination of a frame, and a back, of a lever having at its upper end a slot-and-pin connection with said back, its lower end being pivotally mounted and provided with a toothed sector and another lever pivotally connected with said back and mounted pivotally in said frame and carrying a gear coacting with said sector.

4. In a swing-back car-seat or similar device, a seat-support, annular and spur-gear links pivoted thereto, and a back pivoted to said links.

5. In a swing-back car-seat or similar device, a support, a link, with an annular gear pivoted to said support, and a second link pivoted to the support having a spur-gear meshing with an annular gear and a back pivoted to said links.

6. In a swing-back car-seat or similar device, a seat-support, a plurality of links pivoted to said support one of which is provided with an annular gear, and a back pivoted to said links.

7. In a swing-back car-seat or similar device, a seat-support, a geared link pivoted to said support, a second link pivoted to the support provided with a gear inclosed in a portion of the first-mentioned link, a back pivoted to said links, and stops to limit the movement of said links and back.

8. In a reversible seat, the combination with a frame and a back, of two levers whose upper ends are connected with said back,

one by means of a slot-and-pin connection and whose lower ends are pivotally mounted in said frame one above the other and connecting mechanism for the lower ends of said lever including a toothed sector carried by one of said levers, and a gear engaging therewith which is carried by the other of said levers.

9. In a swing-back car-seat or similar device, a seat-support, two pairs of geared links pivoted to said support, a back pivotally connected with said links, a shaft connecting one link of each pair, and spur and annular gears on said links which are so placed that the link of each pair will positively move the other link through said gearing.

10. In a swing-back car-seat or similar device, a seat-support, two pairs of geared links, one of each pair being provided with the annular gear, and pivotally supported on said support by means of a shaft connecting said links and to which they are fixed, each of said links being engaged by a link provided with a spur-gear, and a back pivoted to said links.

11. In a swing-back seat or similar device, a seat-support, two pairs of geared links pivoted to said support and connected by a shaft to which one of each pair of said links is secured, one of each pair of said links being provided with an annular gear, and the other being provided with a spur-gear engaging said annular gear, and pivoted on a fixed stud, and a back pivoted to said links.

12. In a swing-back seat or similar device, a seat-support, two pairs of geared links pivoted to said support, and connected by a shaft to which one of each pair is fixed, each of said fixed links being provided with an annular gear and a slot concentric with said gear, a second set of links each provided with a spur-gear, and pivoted to a fixed stud which is adapted to slide in the corresponding slot of the other links, so that each spur-gear will engage the corresponding annular gear, a back pivoted to said links, and stops to limit the movement of said back and links.

13. In a swing-back seat or similar device, a seat-support, geared links pivoted thereto, a back pivoted to said links, and a cushion also engaging said links so as when the seat is reversed, the back and cushion are moved in the same horizontal direction.

14. In a swing-back seat or similar device, a seat-support, geared links pivoted to said support, one of said links being provided with an annular gear and a back pivoted to said links, and a cushion engaging certain of said links so that when the seat is reversed, the back and cushion will move in the same horizontal direction.

15. In a swing-back car-seat or similar device, a support, geared links pivoted to said support, one of said links being provided with an annular gear, and a slot, a second link pivoted to a fixed stud which passes

through said slot, and a spur-gear fixed to said second link which engages the annulus of the first link, and back and cushion engaging said links so that when the seat is reversed, the back and cushion will move in the same horizontal direction.

16. In a swing-back car-seat or similar device, a support, geared links pivoted to said support, one of said links being provided with an annular gear, and the other being provided with a spur-gear which is adapted to engage said annular gear, a cushion, a back, and means on said links for moving the cushion and back in unison and in the same horizontal direction.

17. In a swing-back car-seat or similar device, a support, geared links pivoted to said support, one of said links being provided with an annular gear, and another of said links being provided with a spur-gear which is adapted to engage said annular gear, a cushion, a back, means on said links for engaging said back, and means on said cushion for engaging a portion of said links, whereby the back and cushion are moved in unison and in the same horizontal direction when the seat is reversed.

18. In a swing-back seat or similar device, a support, two pairs of links pivoted to said support, and connected by a shaft, a cushion, a back, and means whereby said cushion and back are moved in unison and in the same horizontal direction whenever the seat is reversed.

19. In a swing-back car-seat or similar device, a support, two pairs of geared links pivoted to said support, a shaft connecting said pairs of links, a cushion, a back, and means for connecting said links with the cushion and back, so that when the seat is reversed, the back and cushion are moved in unison and in the same horizontal direction.

20. In a swing-back car-seat or similar device, a support, two pairs of links pivoted to said support, one of each pair being provided with an annular gear, a shaft connecting the links provided with said annular gear, the cushion, a back, and means for moving said back and cushion in unison and in the same horizontal direction when the seat is reversed.

21. In a swing-back car-seat or similar device, a support, two pairs of links pivoted to said support, one of each pair being provided with an annular gear, and the other of said

pair being provided with a spur-gear which is adapted to engage said annular gear, a shaft connecting said links with an annular gear, a back pivoted to said links, and a cushion provided with means engaging certain of said links so that when the seat is reversed, the back and cushion move in unison in the same horizontal direction.

22. In a swing-back car-seat or similar device, a seat - support, a cushion, a back, means for moving the back and seat in the same horizontal direction, and the said means comprising geared links.

23. In a swing-back car-seat or similar device, a support, a cushion, a back, and means for moving said back and seat in the same horizontal direction, said means comprising geared links, one of the gears on said links being an annular gear.

24. In a swing-back car-seat or similar device, a support, a seat, a back, and means for moving said back and seat in the same horizontal direction, said means comprising geared links, certain of said links being provided with annular gears which are provided with stops to limit the movement of the back.

25. In a swing-back car-seat or similar device, a support, cushion-supports positively engaging a portion of said support, a cushion resting on said cushion-support, a back, and means engaging said back and cushion, whereby the back and cushion are moved in unison and in the same horizontal direction when the seat is reversed.

26. In a reversible seat, the combination with a frame and a back, of two levers at one end of said back and connecting said frame and back, one of said levers being provided with a toothed sector and the other with a pinion engaging therewith, substantially as described.

27. In a reversible seat, the combination with a frame and a back, of two levers whose upper ends are pivoted to said back (one by a slot-and-pin connection), their lower ends being pivoted to said frame, a toothed sector actuated by one of said levers and a pinion coacting therewith and actuated by the other, substantially as described.

Signed at the city, county, and State of New York this 18th day of May, 1903.

CHARLES K. PICKLES.
